UNITED STATES PATENT OFFICE.

WILLIAM L. COLEY, OF EAST ST. LOUIS, ILLINOIS.

VENDING-MACHINE.

No. 851,917.

Specification of Letters Patent.

Patented April 30, 1907.

Application filed June 16, 1905. Serial No. 265,499.

To all whom it may concern:

Be it known that I, WILLIAM L. COLEY, a citizen of the United States, and a resident of the city of East St. Louis, county of St. Clair, 5 and State of Illinois, have invented a new and useful Improvement in Vending-Machines, of which the following is a specification.

My invention relates to vending machines 10 and has for its principal objects to simplify the construction of vending machines; to reduce the size of vending machines; to deliver a plurality of the articles to be sold for each coin inserted; to provide a coin chute which 15 can be adjusted for the use of coins of different sizes; to prevent operation of the machine by false coins or tokens; to provide a control pawl arranged to be tripped by a coin in the first instance and by a rotatable star- 20 wheel subsequently for a predetermined number of times; to provide adjustable box-supporting means the position of which is determined by the sides of the box; and other objects hereinafter described and claimed.

25 My invention consists in the parts and in the arrangements and combinations of parts hereinafter described and claimed.

In the accompanying drawings forming 30 part of this specification and wherein like symbols refer to like parts wherever they occur, Figure 1 is a perspective view of the machine one side of the case being removed; Fig. 2 is a longitudinal vertical sectional view; Fig. 3 is a transverse sectional view 35 through the case and a rear view of the mechanism therein; Fig. 4 is a view of the side of the mechanism inside of the case opposite the side shown in Fig. 1; Fig. 5 is a fragmentary view showing the position of the initial portion of the coin chute; Figs. 6 to 9 illustrate the operation of the mechanism controlling the movement of the ejecting member.

To illustrate the invention, a cigar vending machine, in which it is embodied, has been 45 selected although it is to be understood that the major portion of the invention is applicable to machines for vending articles of any description.

The outer case 1 of the machine serves 50 only to support and protect the interior mechanism which is so organized as to be bodily removable from the case. The case is provided with a bar 2 at the lower part of the front side to which the interior mechanism is 55 connected.

The mechanism is provided with side frame plates 3, 4 which are provided at the lower part of their front edges with flanges 5, 6, respectively. A horizontal plate 7 is secured between said frame plates and has a 60 front extension 8 which is shaped to form a receiver. The receiver 8, plate 7 and flanges 5, 6 form a groove adapted to fit over the bar 2 of the case. Screws passing through the flanges 5, 6 secure the frame to the bar 2 and 65 thus the mechanism is securely mounted in the case. Said frame plates have flanges 9, 10 on their front edges extending at right angles to the planes of the plates. These flanges overlap a metallic frame 11 in which a 70 glass plate 12 is mounted. Said plate constitutes the front wall of a chute through which the cigars or other articles to be vended descend to the article ejecting member. It is adjustable. Near its top a shaft 13 is journaled. A knurled enlargement 14 is provided at the center of the shaft. The ends of the shaft project through inclined slots 15, 16 in the frame-plates 3, 4, respectively, and carry gear-wheels 17, 18, respectively. 75 Short racks 19, 20 are secured to said frame plates, respectively, and are arranged parallel with said slots. The lower end of the glass plate is guided by pins 21, 22 extending through inclined slots 23, 24, respectively, 80 in said frame plates and parallel to said slots 15, 16. The slot through which the articles to be vended are ejected lies between the lower edge of said glass plate and said horizontal plate 7. By rotation of said shaft 13, 85 the glass plate can be raised and moved forwardly, simultaneously, or lowered and moved rearwardly, simultaneously, as desired. Thus, the width of the chute and the slot are simultaneously changed in like manner to the desired dimension and thus the same machine may be used to deliver articles of widely differing sizes. To hold the plate to any given position of adjustment, a small 90 detent 25 is pivoted on the frame plate 4 and is provided with teeth to engage the gear-wheel 18 on the shaft 13. The detent is also provided with an arm having a roughened extremity to be engaged by the finger of the operator in manipulating it.

105 Short horizontal guide flanges 26 are struck up from the frame plates and have their top surfaces in the plane of the top surface of the plate 7. Other horizontal flanges 27 are struck up from the frame plates above 110

said flanges 26. The flanges 26, 27 and the plate 7 form the guides for an article ejecting member.

The article ejecting member comprises 5 side plates 28 which are connected by a compound bar at their front ends. They are further connected by a horizontal plate 29 having a vertical flange at its front edge. Said flange and the rear plate of the compound bar form the front and rear walls of the recess in which the cigar or article to be delivered is received from the chute above. Said compound bar comprises a plate 30 which is substantially L-shaped in cross-section and has a short flange at its rear edge and a plate 31 also L-shaped in cross-section, the horizontal flange of which rests immediately beneath the short vertical flange of the plate 30. Screws 32 are pivotally mounted at their ends near the ends of said plate 30 and the flange of the horizontal plate 29. The screws extend through the plate 31 and have screw-threaded engagement therewith. By means of a knurled enlargement 33 the screws may be turned so as to move said plate 31 either forward or backward and thus vary the width of the article-receiving recess. The plate 31 is always so adjusted that its rear surface is in the plane of the rear surface of the plate 12; or in other words, so that the width of the article receiving recess is the same as the width of the chute. The screws 32 are located farther apart than the length of the longest article which is intended to be delivered by the machine.

The article-ejecting member is normally held in its rearmost position by means of springs 34, 35. Said springs are connected 40 to said ejecting-member near the sides thereof, respectively, and at their other ends are connected to a U-shaped frame 36, the legs of which are connected to the frame plates 3, 4. Stops 37, 38 removably attached to the inner faces of the frame plates 3, 4, respectively, prevent the rearward withdrawal of the ejecting member by the springs. When, however, it is desired to so withdraw the ejecting member, the stops can be removed. 45 The corner formed by the horizontal plate 29 of the ejecting member and its vertical flange is cut away almost from side to side and a roller 39 is mounted therein. This roller will engage the cigars or articles in the chute above the cigar being delivered and will turn thus preventing injury to the wrapper which might be occasioned by an unyielding corner.

A knob 40 is secured to the plate 30 of the 50 compound bar forming the front of the ejecting member and which closes the slot through which the articles are ejected. By means of the knob 40 the purchaser can pull out the ejecting member when it has been released by the insertion of a coin.

In addition to the connections hereinbefore described, the frame-plates 3, 4 are further connected by rods 41, 42, 43, the rods 41 and 43 being mounted in the same plane which is inclined downwardly and forwardly 70 and the rod 42 being below said plane. Similar metal slides 44 are mounted on said rods. Each of said slides comprises a sheet metal plate 45 which extends forwardly to the plane of the rearmost position of the 75 glass plate 12 and has a leg extending downwardly into the chute. Each plate 45 has a spacing plate 46 attached to its inner face which conforms to the same shape except that it terminates in an edge at a plane at 80 right angles to the plane of the rods 41 and 43 and said plane is located just in advance of the rod 41. Then a second sheet metal plate 47 is secured to the inner face of each spacing plate 46. The plate 47 conforms to the 85 shape of the plate 45 except that it terminates at its rear lower edge in an edge parallel to the upper edge of the slides 44 and which is spaced therefrom by a distance equal to the thickness of the bottom of a 90 cigar box. Supports for the cigar box are thus provided. One end of the cigar box is broken out. Then its sides are passed between the plates 45, 47 and the bottom passes between the lower edges of the plates 95 47 and the slides 44, the ends of the sides resting on the inclined rear edges of the spacing plates 46. These supports or wings are adjustable and, hence, can support boxes of various widths. The plates 47 being in substantially the plane of the inner surfaces of the box, the wings serve as guides to guide the cigars to the chute leading to the ejecting member. A roller 48 is mounted in the frame-plates 3, 4 just in front of the front edge of a box in position in the frame.

A chamber is formed in front of the box by the wings, described above, and an oscillating bottom 49. The bottom has downwardly extending ears 50 at each side by 100 means of which it is pivoted in the frame plates. At its front end, a vertical plate 51 is pivotally connected. The latter is guided by a rod 52 mounted in the frame plates. The vertical plate 51 constitutes the rear 105 wall of the chute leading from the chamber to the ejecting member. A roller 53 is mounted concentrically with the pivotal connection of the bottom 49 and the vertical plate 51 and said parts are cut away to accommodate the same. This roller is provided to prevent injury to the cigars when the bottom is oscillated. Springs 54 connect the front edge of the oscillating bottom 49 with the flanges 27 and tend to hold said edge 110 in its lowermost position. A corrugated plate 55 is reciprocatingly mounted on said oscillating bottom. The reciprocating plate is connected to the ejecting member by a link 56 which is pivotally connected at each 115 120 125 130 135

end. The oscillating bottom is slotted to accommodate the connection for the link 56 and the reciprocating plate.

Small guard wings 57 are pivotally mounted on the plates 47 and rest at their lower edges upon the oscillating bottom. These guard wings close the space necessarily provided in the guide wings to permit the oscillation of the bottom. As the bottom oscillates and the reciprocating plate moves forward the guard wings are raised, falling immediately when said parts resume their normal positions.

The upper sides of the legs of the U-shaped frame 36 are provided with teeth forming similar racks 58, 59 which terminate at their front ends in stops 60, 61 having curved rear faces. A shaft 62 is journaled in the ejecting member, extends through slots in the frame-plates 3, 4 and carries on its ends rigidly mounted pawls 63, 64 in position to co-operate with said racks 58, 59. Each of said pawls is pivoted at its center and is adapted to engage the rack with either end. At its front end the pawl 63 has a short lateral projection 65 which extends beyond the side of the rack. At its rear end it has a longer lateral projection 66. Both pawls have angular projections on their upper sides above their pivots. The angular projection 67 of the pawl 64 is engaged by a spring 68 mounted on the ejecting member which tends to prevent the turning of the pawl, but when its resistance is overcome causes the pawl to snap quickly into its new position. The angular projection 69 on the pawl 63 has its front face curved for a purpose which will presently appear. A star-wheel 70 is pivotally mounted in position to be engaged by the lateral projections of the pawl 63. The star-wheel has six teeth of which one 71 is offset from the plane of the others so far that it cannot be engaged by the front projection 65 although it may be engaged by the rear projection 66. A detent 72 having a shoulder 73 is pivoted below said star-wheel and is held in contact therewith by a spring 74 connected to the U-shaped frame 36. The shoulder 73 is engaged by said star-wheel and prevents right-handed rotation thereof.

The coin chute consists of two sections. The initial section 75 is inclined downwardly from front to rear and its plane is also inclined to the vertical. On the lower side it is open except for upper and lower flanges 76, 77. The lower flange 76 is cut away for a short distance from the rear end of the section. A substantially vertical section 78 is arranged to receive the coins as they leave the first section 75. It is substantially a channel and is pivoted at its rear upper corner. By means of a screw 79 mounted in a lug on the frame-plate 3 and bearing on a lug on the chute the position of the section can be adjusted. It is clamped in any desired

position by means of a bar 80 and screws 81, 82 entering the frame plate 3. The vertical section 78 of the chute is so adjusted that a coin of the denomination intended to operate the machine will just rest between the pawl 70 and the front flange 83 of the section. A magnet 84 is arranged against the frame plate 3 below the opening in the initial section of the chute formed by cutting away the lower flange 76.

When a coin is inserted in the initial section 75 of the coin chute, it will, if the proper size, rest principally upon the flanges 76, 77. If the coin is too small it will fall out of the initial section. There is a considerable amount of friction between the flanges and the coins as they pass therealong. With the proper coin, this friction is not sufficient to prevent the coin attaining sufficient velocity to jump the gap formed by cutting away a portion of the lower flange 76. But the friction with a disk or token of softer material as lead, paste-board, or the like will be so great that the velocity of the disk or token on reaching the gap will not be sufficient to carry it thereover. Iron or steel disks will be drawn out of the chute by the magnet 84.

A genuine coin of the proper denomination will reach the vertical section 78 of the chute and will fall to the bottom thereof and will be supported by the pawl 63 and the front flange 83 of the chute. This condition is illustrated in Fig. 6. If, now, the ejecting member is drawn forwardly by means of the knob 40, the pressure of the coin will turn the pawl 63 and also the pawl 64 against the resistance of the spring 68 and bring the rear ends of the pawls into engagement with the rack. The ejecting member is now free to be drawn forward as the rear ends of the pawls will slip over the teeth of the racks. As the pawl 63 moves forward its rear projection 66 will engage a tooth of the star-wheel 70. This position is illustrated in Fig. 7. Further movement will turn the star-wheel one tooth against the resistance of the detent 72. When the star-wheel has assumed the position illustrated in Fig. 8, however, the components of the forces acting are such that the resistance of the detent 72 to further rotation of the star-wheel is greater than the resistance of the spring 68 to the tripping of the pawls 63, 64. As the pawl 63 is just leaving engagement with the star-wheel its front end will engage the stop 60 if by any chance the pawls have not been tripped by the star-wheel. This position is illustrated in Fig. 8. When the ejecting member has moved forward far enough for the cigar to fall into the receiver 8 further forward movement is prevented by the engagement of the pawls with the stops 60, 61. The springs 34, 35 will now draw the ejecting member rearwardly. When the projection 65 on the front end of the pawl 63 reaches the star-wheel it will engage

the tooth and turn the wheel until the lower-most tooth strikes the shoulder 73 of the detent 72. This position is illustrated in Fig. 9. The face of the tooth engaged by the projection 65 is now inclined and further rearward movement of the pawl will cause the projection 65 to slide up the inclined face and the pawls will be tripped so as to bring their rear ends into engagement with the racks. The ejecting member can now be moved forward again and in so doing the star-wheel will be advanced one tooth, as before. On its return the pawls will be again tripped by the star-wheel, as before. This cycle of operations will occur five times for the machine illustrated. Upon the return from the sixth forward movement of the ejecting member the offset tooth 71 will occupy the position of the tooth to be engaged by the projection 65 on the front end of the pawl 66. The projection 65 is not long enough to reach the offset tooth, however, and, consequently, the pawls will not be tripped but will remain with their front ends in engagement with the racks. The ejecting member cannot, now, be pulled forward until another coin is inserted. Obviously, the star-wheel might have every other tooth, or every third tooth offset, in which case, the ejecting member could be operated two or three times, respectively, for each coin inserted. As the ejecting member moves forward, by means of the link 56, the corrugated plate 55 is moved forward on the oscillating bottom 49 and the latter is oscillated. These movements agitate the cigars in the chamber in advance of the box and vertically align the cigars over the chute with said chute so that there can be no choking. Obviously, my machine is capable of considerable modification within the scope of my invention and, therefore, I do not wish to be limited to the specific construction shown and described.

What I claim as new and desire to secure by Letters Patent is:

- 45 1. A vending machine comprising a manually actuated ejecting member, a pawl arranged to normally prevent ejecting movement of said member and to be rendered ineffective by a coin, a star wheel having teeth in different planes, the teeth in one plane being arranged to trip said pawl on both its forward and rearward movements and the tooth in the other plane being arranged to trip said pawl on its forward movement only, said wheel being automatically rotated in one direction by engagement with said pawl and a detent to prevent rotation of said wheel in the opposite direction.
- 50 2. A vending machine comprising a frame, an ejecting member movably mounted in said frame, a rack mounted on said frame, a reversible pawl mounted on said ejecting member and arranged to engage said rack with either end, the teeth of said rack being

so spaced as to permit a slight initial movement of said ejecting member when the front end of said pawl is in engagement with said rack, and said pawl being arranged to be reversed by engagement with a coin.

3. A vending machine comprising a frame, an ejecting member movably mounted in said frame, a rack arranged to be engaged by either end of said pawl, and a stop on said frame in position to support a coin seated in said seat when said pawl is in its normal position and to prevent the movement of said coin with said pawl, whereby said pawl will be reversed by the ejecting movement of said ejecting member and means to reverse said pawl as said ejecting movement is being completed.

4. A vending machine comprising a frame, an ejecting member movably mounted in said frame, a rack mounted in said frame, a pawl mounted on said ejecting member arranged to normally engage said rack to prevent ejecting movement of said member, and an adjustable stop mounted on said frame, said stop and said pawl in its normal position being arranged to support a coin in such a position that relative movement of said stop and pawl will trip said pawl and permit ejecting movement of said ejecting member.

5. A vending machine comprising a frame, an ejecting member movably mounted in said frame, a pawl mounted to move with said member and having a seat for a coin, a rack on said frame arranged to be normally engaged by said pawl to prevent ejecting movement of said ejecting member, and a coin-chute adjustably mounted on said frame and terminating near the normal position of said pawl, one wall of said chute being arranged to support a coin seated in said seat in said pawl.

6. A vending machine comprising a coin chute, an ejecting member, a pawl and a rack arranged to prevent ejecting movement of said ejecting member but permitting an initial movement thereof, said pawl being arranged to support a coin at the lower end of said chute, whereby upon actuation of said ejecting member said pawl will be tripped and rendered ineffective to prevent ejecting movement of said member.

7. A vending machine comprising a frame, an ejecting member movably mounted in said frame, a rack mounted on said frame, a reversible pawl carried by said ejecting member and arranged to engage said rack with either end and normally preventing ejecting movement of said member, a coin-chute terminating above the position of said pawl when said ejecting member is in its rearmost position, a flange of said chute and said pawl being arranged to support a coin, whereby

- 5 said pawl will be tripped when said ejecting member is moved forward and will be rendered ineffective to prevent movement of said member.
- 10 8. A vending machine comprising a frame, an ejecting member movably mounted in said frame, and mechanism to control the movement of said ejecting member comprising a reversible pawl, a rack arranged to be engaged by either end of said pawl, said pawl and said rack being normally arranged to prevent ejecting movement of said ejecting member, means to initially reverse said pawl by movement of said ejecting member when a coin is inserted, a star-wheel having a tooth arranged to trip said pawl as said ejecting member is completing its full forward movement and its full rearward movement and a tooth arranged to trip said pawl as said ejecting member is completing a full forward movement but not when it is completing a full rearward movement.
- 15 9. A vending machine comprising a frame, an ejecting member movably mounted in said frame, and mechanism to control the movement of said ejecting member comprising a reversible pawl mounted to move with said member, a rack mounted on said frame in position to be engaged by either end of said pawl, and a star-wheel having teeth arranged to be engaged by said pawl and to reverse the same both when it is moving forwardly and rearwardly and a tooth arranged to be engaged by one end of said pawl only to reverse the same when it is moving in one direction only.
- 20 10. A vending machine comprising a frame, an ejecting member movably mounted in said frame, mechanism to control the movement of said ejecting member comprising a reversible pawl having lateral projections of different lengths on its front and rear ends, respectively, a rack arranged to be engaged by either end of said pawl, and a star-wheel having a plurality of teeth arranged to be engaged by both of said projections of said pawl, and a tooth arranged to be engaged by only one of said projections of said pawl.
- 25 11. A vending machine comprising a frame, an ejecting member movably mount-
- ed in said frame, mechanism to control the movement of said ejecting member comprising a reversible pawl having lateral projections on both ends, one of said projections being longer than the other, a rack arranged to be engaged by either end of said pawl, and a star-wheel having a plurality of teeth in the same plane arranged to be engaged by either of said projections and a tooth in a plane parallel to the plane of said teeth and arranged to be engaged by only the longer of said projections. 55
- 30 12. A vending machine comprising a frame, an ejecting member movably mounted in said frame, a reversible pawl mounted to move with said member and having lateral projections of different lengths on its front and rear ends, respectively, and a coin seat, a rack arranged to be engaged by either end 60 of said pawl, a coin-chute terminating near the normal position of said pawl, one wall of said chute being arranged to support a coin on said seat of said pawl in position to trip said pawl upon relative movement of said pawl and said chute, and a star-wheel having teeth arranged to be engaged by both 65 projections of said pawl to trip the same, and a tooth arranged to be engaged by one only of said projections on said pawl. 70
- 35 13. A vending machine comprising a frame, an ejecting member reciprocatingly mounted in said frame, a shaft pivotally mounted on said member, reversible pawls rigidly mounted on the opposite ends of said shaft, racks arranged to be engaged by said pawls, respectively, a spring engaging one of said pawls and arranged to hold either end of said pawls in engagement with said racks, means to reverse said pawls by the intervention of a coin, and means to reverse said pawls subsequent to the reversal by the insertion of a coin. 85
- 40 In testimony whereof I have signed my name to this specification in the presence of 90 two subscribing witnesses this 14th day of June, 1905, at St. Louis, Missouri.
